Robert L. Wooding, Wolcott, Conn., assignor to
Robertshaw Controls Company, Richmond, Va.

Filed Oct. 25, 1973, Ser. No. 409,375

Term of patent 14 years

Int. Cl. D10—01

U.S. Cl. D10—2

FIG. 1

FIG. 2

FIG. 3

FIG. 4

FIG. 1 is a front view of a control panel for clock and timer showing my new design;

FIG. 2 is a top plan view thereof, the bottom plan view being identical thereto;

FIG. 3 is a left side view thereof; and

FIG. 4 is a right side view thereof.

The broken line showing of the rear clock structure in FIGS. 2, 3 and 4 is for illustrative purposes only and forms no part of the claimed design.

I claim:

The ornamental design for a control panel for clock and timer, substantially as shown and described.
